Primary Examiner — Karen E Kearney*Assistant Examiner* — Michael Chong(74) *Attorney, Agent, or Firm* — Wagenknecht IP Law Group, PC(57) **CLAIM**

The ornamental design for an outlet tap adapter, as shown and described.

DESCRIPTION

FIG. 1 is a front, top, and left perspective view of an outlet tap adapter showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings represent portions of the article that form no part of the claimed design.
